CLAIM

(51) **LOC (11) Cl.** **07-99**

The ornamental design for a cover, as shown and described.

(52) **U.S. Cl.**

DESCRIPTION

USPC **D7/393**

FIG. 1 is a top perspective view of a claimed design;
FIG. 2 is a top perspective view of FIG. 1, shown in a configuration of use;

(58) **Field of Classification Search**

FIG. 3 is a front view of FIG. 1;

USPC D7/391, 412, 413, 300, 601, 323, 339,

FIG. 4 is a rear view thereof;

D7/347, 354, 409, 402, 550.1, 355;

FIG. 5 is a right side view thereof, with the left side view
D3/273, 276, 280, 282, 283, 284;
being a mirror image;

D9/516, 558

FIG. 6 is a top view thereof; and,

CPC .. A47J 36/06; A47J 47/14; B65D 1/22; B65D
1/34; B65D 1/40; B65D 1/165; B65D

FIG. 7 is a cross-sectional view taken along and in the
15/02; B65D 1/00; B65D 1/26
direction of line 7-7 in FIG. 6.

See application file for complete search history.

The dash-dash broken lines illustrate portions of the cover
that form no part of the claimed design. The dash-dot broken
lines illustrate the boundaries of the claimed design. The
cover is shown with symbolic breaks. The appearance of any
portion of the cover between the break lines form no part of
the claimed design.
